DESIGN FOR A HANDLE STICK

Richard J. Cowling, New York, N. Y., assignor to Joe Lowe Corporation, New York, N. Y., a corporation of Delaware

Application June 10, 1936, Serial No. 63,186

Term of patent 14 years

To all whom it may concern:

Be it known that I, Richard J. Cowling, a citizen of the United States and resident of New York, New York, have invented a new, original, and ornamental Design for a Handle Stick, of which the following is a specification, reference being had to the accompanying drawing, forming part thereof.

The figure of the drawing is a perspective view of a handle stick embodying my new design.

What I claim is:

The ornamental design for a handle stick substantially as shown.

RICHARD J. COWLING.
